Primary Examiner — Cynthia M. Chin(74) *Attorney, Agent, or Firm* — Millman IP Inc.(57) **CLAIM**

The ornamental design for a construction toy element, as shown and described.

DESCRIPTION

FIG. 1 is a perspective view from above and to one side of the new design for a construction toy element;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a front elevation view thereof.

The broken lines are for the purpose of illustrating portions of the article that form no part of the claim.

1 Claim, 7 Drawing Sheets(56)
